UNITED STATES PATENT OFFICE.

WILLARD F. BARNES, OF MILL VALLEY, CALIFORNIA, ASSIGNOR TO S. V. BARNES, OF MILL VALLEY, CALIFORNIA.

BASKET-MAKING MACHINE.

1,301,355.

Specification of Letters Patent.

Patented Apr. 22, 1919.

Application filed May 12, 1915. Serial No. 27,693.

To all whom it may concern:

Be it known that I, WILLARD F. BARNES, a citizen of the United States, residing in Mill Valley, county of Marin, State of California, have invented new and useful Improvements in Basket-Making Machines, of which the following is a specification.

This invention pertains to automatic machines of the class used to manufacture baskets, boxes, cartons, crates, barrels and other receptacles made of very thin sheets or slices or veneers of wood, or other suitable materials or substances, and bound or reinforced by a metallic strip or strips, or other suitable material or materials, or substance or substances.

An important object of my invention is the provision of a machine, simple in construction, that will greatly reduce the amount of waste material, caused by deformation of the baskets, boxes, cartons, crates, barrels or other receptacles, so frequently occurring in machines as at present constructed.

Another important object is to provide a machine that will manufacture baskets, boxes, crates, cartons, barrels and other receptacles, of any size or shape, made of very thin sheets, or slices, or veneers of wood, or other suitable materials or substances, and bound or reinforced by a strip or strips of metal, or other suitable substances.

Another important object is to provide a machine that will attain a maximum productive efficiency per hour and be economical in power consumption.

Other objects will become manifest.

It is desired to provide a machine that will form or manufacture a basket, box, crate, carton, barrel or other receptacle of two pieces, or sheets, or slices, or veneers, of wood, or other suitable material or substance (which will be referred to hereinafter as slices), that have been previously shaped and sized in blank, by automatically placing one across the other, bending the projecting portions to form the sides and then binding the edges to form the permanent basket, box, crate, carton, barrel or other receptacle, and ejecting the same from the machine. Any thickness of bottom and sides may be attained by using, as the case may be, more than one set of slices.

My invention comprises details of construction, the elements and the combination

of elements, and will be clearly explained by reference to the drawings, in which—

Figure 1 is an end elevation and section through the mold. Fig. 2 is a perspective view of the buffer. Fig. 3 is a perspective view of the binding-strip bending frame. Fig. 4 is an enlarged view of the binding-strip cutter knife. Fig. 5 is a plan view. Fig. 6 is a front elevation. Both Figs. 5 and 6 show the grouping and the connection of the tin cutting and V or U shaping machines and the binding-strip cutter knife and the binding-strip bending frame, as well as the automatic slice delivering device, with the modified basket or other receptacle making machine proper.

The embodiment of my invention as shown in Figs. 1, 5 and 6 comprises a cross-arm carrier 1 carrying four or more formers 2, one on each arm. These formers 2 are held in position by screws 3, through corresponding slots in the arms. Each former 2 has a centrally located extension for the purpose of holding and guiding the sliding shank 62 of presser-foot 63 as shown in Fig. 1. This former extension fits in a slot in the arm of the cross-arm carrier 1. Sliding shanks 62 are provided with pressing springs 75 which press against the sides of the former extension, thus holding the sliding shanks 62 by means of friction. On the upper ends of the sliding shanks 62 are attached the adjusting sleeves 76 by the screws 59. Each former 2 is provided with the pins 23 of suitable size projecting out and downward around the rims. By this means the slices of whatever material or substance are picked up and held. When forming the baskets or other receptacles, the cross-arm carrier 1 lowers the formers 2 over the buffer 25 and the mold-block 24. The presser-foot 63 is held back in this downward movement by the buffer 25, causing the slices to be held between their two plates, while the sliding shank 62 of the presser-foot 63 is protruding in its entire length above the former extension. The pressing springs 75 are holding it in this position in the former extension, while the former 2 with the finished basket or other receptacle in it is raised back into its original position and is then carried around one quarter section.

The basket ejector-plate 26 is fastened by the set-screws 27 on a horizontally swinging arm 28 which is held in position by the

spring 29 and the adjusting sleeve 30 with the screw 31 on the vertical rod 32 attached to the frame.

Wherever the word "basket" is used in 5 the specification, it is intended also to refer to any receptacle that may be made or manufactured by this machine.

Every time the cross-arm carrier 1 turns one quarter section, the protruding sliding 10 shank 62 of the presser-foot 63 engages the ejector-plate 26 on the swinging-arm 28 and pushes it aside, tensioning the spring 29. After this movement the cross-arm carrier 1 descends carrying the former 2 with the finished basket, and the presser-foot 63 lowers its sliding shank beneath the ejector-plate 26 and thus releases the ejector-plate 26, so that the ejector-plate 26 will swing back into its former position above the top of 20 the sliding shank 62. The lifting of the presser-foot 63 with the sliding shank 62 is prevented by the ejector-plate 26 during the following upward movement of the cross-arm carrier 1 with the former 2. This movement simultaneously causes the ejection of 25 the finished basket on to the conveyer 33.

The stopper 4 fits in the corresponding notches on the ends of the cross-arm carrier 1, holding it in position during the period 30 the basket is being made. The stopper 4 is held by the hinge 5 and is operated by the cam disk 6 on the driving shaft 97.

The cross-arm carrier 1 is fastened by bolts 7 to the top plate 8 of the revolving 35 sleeve 106, and is turned with the same.

The revolving sleeve 106 revolves in a bushing 13 of which the arm extension 14 is attached to the angle irons 15, which are fastened to the main frame. In the revolving 40 sleeve and in the square box on the bottom extension 16, the arbor-rod 9 is guided. The lower part of this rod is square to keep it from turning with the revolving sleeve. The lifting and lowering of the arbor-rod 9 45 is effected by means of a rack 17 attached to the arbor-rod 9 engaging the spur gear 18 on the shaft 19 which is turned by the gear 20 driven by the rack 21 connected to the oscillating link 60. This oscillating link 50 60 derives its movement from the cam 61 on the driving shaft 97. The shaft 19 is held by the bearings 22 on the bottom extension 16.

The revolving sleeve 106 is turned by a 55 ratchet-lever 105, the arm of which is linked to the crank arm 104 on the shaft 93.

The arbor-rod 9 supports, lifts and lowers the sleeve 106 with the cross-arm carrier 1, for the purpose of picking up the slices, 60 forming and ejecting the finished basket.

The revolving sleeve 106 and the cross-arm carrier 1 are kept in position on the arbor-rod 9 by the adjusting sleeves 10 which are fastened to the arbor-rod 9 by the set 65 screws 11. The cushion spring 12 is inserted

between the top of cross-arm carrier 1 and the upper adjusting sleeve 10.

In Fig. 2 is shown the buffer 25 with hinges 34 on all four sides, shaped in such manner as to allow an upward turning, but preventing the hinges from turning them below the horizontal plane, thus preventing the binding-strips from catching, or being pulled off, or loosened, during the upward movement of the former 2 and during the 75 period of the ejection of the finished basket.

In Figs. 1, 3 and 5, is shown various parts of the binding strip bending frame of five bending links 35, 35^a, 35^b, 35^c and 35^d. The middle bending link 35 has a forward and 80 backward movement through the two slots in which are located the pins 36, fastened to the frame plate 37. In the first movement to bend the binding strips around the mold-block 24, the five bending links move forward in line with the forward movement of the middle bending link 35, before the bending links 35^a, 35^b, 35^c and 35^d commence to fold around the mold-block 24. The bending links 35, 35^a, 35^b, 35^c and 35^d are linked 90 together by the hinge-pins 38. The push-rods 39 are connected with toggle-links 40 through the pin 41 in the push-rods 39 and working in the slots in the toggle-links 40. The toggle-links 40 are connected with the bending links 35^a and 35^d by the pins 41^a so that the bending links 35^a and 35^d will turn easily. The folding of the bending links 35^a, 35^b, 35^c and 35^d around the mold-block 24 is effected by the action of the push-rods 39 and the toggle-links 40. The push-rods 39 are given a reciprocating forward and backward movement by means of the levers 64 (Figs. 1 and 5) keyed on the horizontal shaft 65 which is supported by the 100 bearings 66, the levers 64 being actuated by the cam disk 69 (Fig. 4) on the main shaft 97, through the connecting rod 68 to the arm 67 which is keyed or held in place on the horizontal shaft 65. The bending link 105 35^d, while being folded around the mold-block 24, slides up on the raiser 42, so that the end of the binding-strip which it is bending around the mold-block 24 will clear the other end of the binding-strip being bent 110 around the mold-block 24 from the opposite direction by the bending link 35^a, and so that, when the end of the binding-strip bent around the mold-block 24 by the bending link 35^a is in place, the other end of the 120 binding-strip bent around the mold-block 24 by the bending link 35^d snaps into place in the end of the binding-strip bent by the bending link 35^a, so as to make a connection varying in length according to the length of 125 the binding-strip.

The slices are automatically fed from the hoppers 45 by suitable conveyers, in the drawings shown as endless belts 46 on the pulleys 46^a on the shaft 46^b and on the pul- 130

leys 46^c on the shaft 46^d, and the endless belts 47 on the pulleys 47^a on the shaft 47^b and on the pulleys 47^c on the shaft 47^d, and the endless belt 48 on the pulley 46^e on the extension of the shaft 46^d and on the pulley 47^e on the extension of the shaft 47^d.

Also illustrated is shown simple lever 43, connected through the rod 44 with the swinging arm 70 on the shaft 93 which is 10 rocked by the eccentric 98, eccentric-rod 99 and the crank-arm 100. The lever 43 through an adjustable connecting-rod 71 turns the spur gears 72 by means of ratchet wheel 73, and drives the shaft 46^d, the shears 15 57, the feeder rollers 59 and the forming-strip bending rolls 81.

The carrier bars 44 attached to the endless chain or belt 46 engage the bottom slices and carry them one at a time on to the endless 20 belts 47 over the support plates 49 to the stoppers 54 on the support plates. The support plates 49 are attached to the slice-guides 50 by means of the brackets 51 and the screws 52. These slice-guides 50 are 25 secured to the angle-irons 15 with the screws 53 (shown in Fig. 1), and are suitably recessed to allow the descending former 2 to pick up the slices resting on the belts 47 and on the support-plates 49. In this 30 movement of the former 2 the first slice is picked up by the former 2 and carried around and placed upon the second slice at right angles so as to form what is known as a "Maltese cross." With the slices in this 35 position the former 2 also picks up the second slice and carries both around and places them upon the mold-block 24.

The binding-strips are cut to suitable width by the shears 57 automatically worked 40 up and down by any suitable mechanism, out of sheet tin or other suitable metals or substances fed up on the plate 58 by the feeder rollers 59. As soon as the binding-strips are cut off, they drop into a channel 45 and are forwarded by the mechanism of the shaping device 80 along the channel into contact with the shaping rolls 81 which bend or form the binding-strips into a V or U shape, and until they are in line with 50 and in front of the bending-links 35, 35^a, 35^b, 35^c and 35^d of the bending frame.

In case the binding-strips are fed in from 55 reels of tin or other suitable metals or substances by suitable mechanism, instead of cutting the binding-strips out of sheet tin, then the cutter knife 82 is used to cut the binding-strips at the proper time to the required length.

In Fig. 4 is shown an enlarged view of 60 the cutter-knife 82 shown in Fig. 1. The cutter-knife 82 is shown mounted in the holder 84 which is carried on the slide 65. This is raised and lowered on the ways 86 by the lever 87 and the rod 88 (Fig. 1) which oscillates on the pin 89, ec-

centrically located on the main shaft 97. The kinking-dies 83 (Fig. 1), secured in their respective die holders 92, derive their movement from the up and down action of the lever 87, through the bar 91 secured to 70 the hinge-rod 90 attached to the lever 87. There are as many kinking-dies 83 as are required. Simultaneously with the operation of the cutter-knife 82, the kinking-dies 83 are putting kinks or indentations in the 75 inner side of the binding-strips at suitable points where it is to be bent or folded. Fig. 4 shows the V-shaped tin 95 in the V-shaped space between block 94 and block 96. These two blocks form the set.

The binding-strips may also be fed from a reel of proper width, thus eliminating the necessary automatic cutting by shears as hereinbefore described.

The shape of the mold-block can be 85 changed so as to make or manufacture a basket of any number of sides or of any shape desired. Where this is done, the mechanism hereinbefore described can be so altered and added to so as to meet the different sided and shaped baskets, as for illustration the number of the bending links can be increased from five to whatever number of bending links is necessary to make the required sided basket.

Having thus described my invention what I claim and desire to secure by Letters Patent is:—

1. In a basket-making machine of the character described, a stationary mold-block, a cross-arm carrying formers on each arm, mechanism by which said cross-arm is raised and lowered, and also given a revolving movement so that the reciprocating formers will co-act with the mold-block, and means for folding slices over said mold-block, said means consisting of formers of such shape as to make the desired form of basket or other receptacle.

2. In a basket-making machine of the character described, a mold-block, formers co-acting with the mold-block to fold slices into basket shape, means for placing the slices transverse upon the mold-block, means for retaining the slices in position in the formers during the subsequent operations, said means including a buffer, and a presser-foot with a sliding shank, means for holding and guiding the sliding shank, said means being a centrally located extension of the formers, means for holding the sliding shank in position, said means including pressing springs located in channels in the sliding shank and which press against the sides of the former extension, and an adjusting sleeve attached to the upper end of the sliding shank by a screw.

3. In a basket-making machine, a mold-block so situated as to receive reciprocating formers co-acting therewith, means for plac-

80

95

120

125

130

ing slices at right angles with each other, said means including four pairs of carrier belts or endless chains properly timed, carrier bars suitably located on the first two pairs of belts, support plates and stoppers located on the support plates so as to stop the advancing slices when at right angles with each other, reciprocating formers co-acting with the mold-block, and means for picking up the slices, said means including pins of suitable size projecting out and downward around the rims of the formers.

4. In a basket-making machine, means for advancing slices, means for picking up the slices, said second named means including formers with pins, a mold-block, mechanism for reciprocating the formers so as to co-act with the mold-block, means for retaining the slices in position under the formers and over the mold-block, means for ejecting the finished basket, said means including an ejector-plate on a swinging arm, a sliding shank which engages the ejector-plate, and pushes it aside, engaging a spring, mechanism by which the sliding shank is raised to engage the ejector-plate in the upward movement, and a presser-foot at the lower end of the sliding shank, which said presser-foot ejects the finished basket in the following downward movement of the sliding shank by the same mechanism.

5. In a basket-making machine, a mold-block, formers, means for picking up slices, means for advancing the slices, said second named means including four pairs of endless chains or belts on pulleys operated by shafts, two of said shafts being also connected by an endless chain or belt on pulleys, and one of said last mentioned shafts being driven by a lever which through an adjustable connecting rod turns the spur gears by means of a ratchet wheel, carrier bars attached to the first two pairs of endless chains or belts, slice-guides, support plates attached to the slice-guides by means of brackets with screws, said slice-guides being secured to angle-irons with screws and being suitably recessed to allow the former to pick up the slices resting on the belts and support plates, and stoppers situated on the support plates.

6. In a basket-making machine, a mold-block, formers, reciprocating and co-acting with the mold-block, means for advancing slices, means for picking up the slices, means for reciprocating the formers to co-act with the mold-block, means for holding the slices in position, means for folding the slices to conform to the sides of the mold-block, and means for bending binding-strips around the mold-block.

7. In a basket-making machine, a mold-block, formers, mechanism by which the formers are reciprocated to co-act with the mold-block, means for advancing slices,

means for picking up the slices, means for placing the slices transverse upon the mold-block, means for folding the slices on the mold-block into basket shape, means for forming V-shape binding-strips out of sheet tin, said means including feeder rollers for advancing the tin into position to be cut, cutter shears, a channel in front of the cutter shears into which the strips as cut drop, mechanism for advancing the strips substantially as herein described, and shaping rolls for forming the strips into V-shape.

8. In a basket-making machine, a mold-block, reciprocating formers co-acting therewith, means for advancing V-shape formed binding-strips as substantially herein described, means for cutting the binding-strips into proper length when fed in from reels of proper width, said means including a cutter knife mounted in a holder carried on a slide on ways, and means for raising and lowering the slide, said means including a lever and a rod which oscillates on a pin eccentrically located on the main shaft.

9. In a basket-making machine of the character described, means for forming V-shape binding-strips, mechanism substantially as described for advancing the strips when formed, means for kinking or indenting the strips at points where they are to be bent, said means including kinking-dies secured in their respective die-holders, and means by which the kinking-dies are operated, said means including a lever through a bar attached to the die-holders and secured to a hinge rod attached to said lever, all operably mounted.

10. In a basket-making machine, a mold-block, means for bending binding-strips around the mold-block, said means including a binding-strip bending frame of five or more bending links, push-rods, toggle-links operably connected with the push-rods through pins in the push-rods and working in slots in the toggle-links, the middle bending link having a forward and backward movement through two slots in which are located pins fastened to the frame plate, means for giving the push-rods a reciprocating backward and forward movement, said means including levers keyed on a horizontal shaft supported by bearings, a cam disk on the main shaft, an arm keyed on said horizontal shaft, a connecting rod, all operably connected up substantially as described, a raiser, means for joining the ends of the binding-strips, said means including mechanism by which one of the outer bending links, while being folded around the mold-block, slides up on the raiser so that the end of the binding-strip that it is bending around will clear the other end of said binding-strip being bent around the mold-block from the opposite direction, and when the latter end is in place, the former end will

snap into place in the latter and thereby make a connection varying in length according to the length of the binding-strip.

11. In a basket-making machine of the character described, a mold-block over which slices are folded into basket shape, a former, means for advancing the slices to position at right angles to each other, means for picking up the slices, means for raising the former and carrying it around to the mold-block upon which the basket is to be made, means for bending binding-strips around the mold-block, means for retaining the slices in the former until the basket is completed, and means for ejecting the finished basket.

12. In a basket-making machine, a mold-block, formers, means to prevent the binding-strips from catching, or being pulled off, or loosened during the upward movement of the former in which the basket is made, and during the ejection of the finished basket, said means including a buffer located in the top of the mold-block as herein described, with the outer four edges hinged to the main

part of the buffer and shaped in such a manner as to allow an upward turning, but preventing the hinges from turning the edges below the horizontal plane.

13. In a basket-making machine, the combination of means for cutting binding-strips out of sheet tin, of means for forming the strips into V-shape, with means for advancing slices to position at right angles with each other, through mechanism operably connected up as described.

14. In a basket-making machine, the combination of means for cutting binding-strips into proper length from reels of tin of proper width, with means for kinking or indenting the strips at the points at which they are to be bent around the mold-block.

In testimony whereof, I have hereunto set my hand in the presence of two subscribing witnesses this 5th day of May, 1915.

WILLARD F. BARNES.
